US0D1028277S

(12) **United States Design Patent** (10) **Patent No.:** **US D1,028,277 S**
(45) **Date of Patent:** **** May 21, 2024**

(54) **TESTING DEVICE**

(71) **Applicant:** **SPD Swiss Precision Diagnostics GMBH**, Geneva (CH)

(72) **Inventors:** **Paul J. Laverack**, Leighton Buzzard (GB); **Sunil Kalbandi**, Redlodge (GB); **James Gani**, Bedford (GB)

(73) **Assignee:** **SPD Swiss Precision Diagnostics GMBH**, Geneva (CH)

(**) **Term:** **15 Years**

(21) **Appl. No.:** **29/786,799**

(22) **Filed:** **Jun. 2, 2021**

Related U.S. Application Data

(62) Division of application No. 29/708,010, filed on Oct. 2, 2019, now Pat. No. Des. 935,049.

(57) **CLAIM**

The ornamental design for a testing device, as shown and described.

DESCRIPTION

FIG. 1 is a top perspective view of a testing device with its cap on;

FIG. 2 is a side view of the testing device with its cap on;

FIG. 3 is a top view of the testing device with its cap on;

FIG. 4 is a bottom view of the testing device with its cap on;

FIG. 5 is an enlarged first end view of the testing device with its cap on.

FIG. 6 is an enlarged second end view of the testing device with its cap on; and,

FIG. 7 is a top perspective view of the testing device with its cap off.

The broken lines in the figures depict portions of the test device comprising a pipette holder that form no part of the claimed design. The dot-dashed broken lines depict the boundaries of the claim and form no part thereof.

1 Claim, 7 Drawing Sheets
